UNITED STATES PATENT OFFICE.

DANA H. BENJAMIN, OF CLEVELAND HEIGHTS, OHIO, AND JAMES P. McCARTHY, OF CHICAGO, ILLINOIS, ASSIGNEES TO THE AMERICAN LAUNDRY MACHINERY COMPANY, OF NORWOOD, OHIO, A CORPORATION OF OHIO.

PRESSING MACHINE.

Application filed April 3, 1918. Serial No. 226,503.

To all whom it may concern:

Be it known that we, DANA H. BENJAMIN and JAMES P. McCARTHY, citizens of the United States, residing at Cleveland Heights and Chicago, respectively, in the counties of Cuyahoga and Cook, respectively, and States of Ohio and Illinois, respectively, have invented certain new and useful Improvements in Pressing Machines, of which the following is a specification.

This invention relates to pressing machines, and particularly to the work supports therefor. The invention is particularly adaptable for use in pressing sweaters, underwear or other knitted woolen fabrics or articles, but is capable of use with any desired materials or articles.

In pressing knitted sweaters or like knitted articles in a pressing machine, the article is usually laid upon a canvas or other fabric support over a yielding pressing bed and while thereon is subjected to the pressure of a heated superposed metal surface. Sometimes a layer of canvas or padding is interposed between the article and the heated upper surface. Experience has shown that when knitted woolen articles are pressed in this manner the heat and moisture cause the colors in the article to run, producing undesirable discoloration which materially detracts from the appearance and salability of the articles. The effect is probably also due to the action of the heated ironing plate exerted through only a canvas layer. Indeed, it is frequently found that an imprint of the threads of the canvas is produced upon the fabric of the knitted article, which is an additional detriment to its appearance.

The object of the present invention is to provide suitable means which enables sweaters or like knitted articles to be pressed in pressing machines and therefore rapidly and conveniently, but nevertheless without any liability of producing discoloration or an imprint of the pressing canvas upon the article. A further object of the invention is to provide suitable means for this purpose which is of simple form and can be readily applied to any form of pressing machine, and which in certain types of machine assists in holding the articles to be pressed in the proper shape and form.

The invention comprises the construction and arrangement of parts hereinafter described and claimed.

In the drawings, Fig. 1 represents an elevation of one form of pressing machine embodying the invention; Fig. 2 is a plan view of the work holder, parts being broken away to expose the lower layers; Fig. 3 is a cross section on the line 3—3, Fig. 2 the cover layer being shown in elevated positions; Fig. 4 is a plan view of the work supporting member of another form of pressing machine; and Fig. 5 is a cross section, on the line 5—5, Fig. 4, and illustrating the two co-operating pressing members with the cover layer for the garment in elevated position.

The invention may be applied with equal facility to various types of pressing machines. For purposes of illustration, and not in any sense as limiting the invention, Figs. 1 to 3 inclusive show the invention applied to what is known as an underwear press. This press, as to most of its features, is of the same form shown in the prior patent to Daniel M. Cooper, granted May 11, 1915, No. 1,139,346, to which reference may be had for a more complete description of said machine. Briefly described the machine comprises a suitable frame 1, having an upper pressing member or head 2 suitably heated, such as by steam introduced to its inner cavity, and which head co-operates with a padded lower pressing member or bed 3. The bed may also be heated in a manner similar to the head. It is located below and in registry with the head, and the work to be pressed is subjected to pressure between said members by relative movement thereof. One of said members 2 and 3, such as the bed 3, is vertically movable relative to the other, the operating mechanism therefor consisting of toggle members 4 connected to a nut 5 actuated by the rotating movement of a screw 6 operated by the driving gear 7. As the screw is rotated in one direction or the other the toggle is straightened or broken and the bed elevated or lowered along its vertical guides.

For conveniently handling the work the articles to be pressed are laid in turn upon a work holder 8, which is moved in laterally, by sliding movement along guides 8^a.

as shown in said Cooper patent, to position between the pressing members so that relative vertical movement thereof will press the articles. One of the work supports is 5 illustrated in detail in Figs. 2 and 3.

Each work support comprises a rigid outer frame 10 having secured thereto, such as by lacings 11, a supporting layer 12 of canvas or other flexible fabric upon which 10 the articles to be pressed are supported. When the work support or tray is in position between the pressing members the canvas layer 12 comes next above the padding of the lower pressing member 3. The work 15 support, with the articles thereon, is elevated with the lower pressing member into co-operating pressing relation with the head.

For the purposes of this invention, each 20 work support, of which several may be used with each machine, is provided with a cover member 13. This member is attached to the work support in such a manner that the articles to be pressed can be readily laid beneath the cover member and upon the canvas layer 12 and the cover member laid 25 down in position above the articles. This effect can be obtained in any suitable manner, for example, by securing one edge of the cover member to the canvas layer 12 by 30 stitching or by the buttons or button fasteners 14 spaced at intervals along said edge. The securement of the cover member to the canvas layer 12 along this edge is preferably permanent but may be detachable if 35 desired. Along its opposite edge the cover member may be connected to the canvas layer 12, such as by snap fasteners 15, so that it can be ripped loose from the canvas layer along this edge and turned back to 40 remove or apply articles to be pressed.

The cover layer 13 may be of any suitable construction for the purpose, its essential characteristic being the provision of a layer of woolen fabric which will contact directly 45 with the knitted articles to be pressed. The cover layer for example may be made entirely of woolen fabric, but for strength and durability is shown in the drawings as consisting of a body layer 16 of canvas to the 50 under surface of which is secured, as by the stitching 17, a layer 18 of woolen fabric.

With the arrangement described the articles to be pressed are applied to the work support while the latter is out of range of the pressing members. In this position the cover member is loosened by unfastening the snap fasteners 15 and is turned back to enable the articles to be pressed to be properly arranged on the canvas layer 12. The cover 55 is then turned down and refastened at the fasteners 15. The work support is then moved to position between the pressing members and pressure is applied thereto. While being moved laterally into position between 60 the bed and head the cover member of the

work support holds down the folded garments and prevents them from becoming disarranged, it being unnecessary to insert the hands near the heated head to adjust disarranged articles. It will, of course, be understood that the articles or the upper and lower layers of the work support may be moistened, either by spraying water thereon, or by applying steam thereto, or the articles may be pressed without special moistening 70 as they usually absorb enough moisture from the surrounding atmosphere for pressing purposes. When the pressing members come together the article to be pressed is subjected below to the action of the yielding bed and the layer of canvas, while above it is subjected to the pressure of a heated metal surface through a layer or layers of canvas and the woolen layer 18. As a consequence 75 there is no liability to produce an imprint 80 of the fabric of the canvas upon the garment or to produce discoloration or running of the colors therein.

Figs. 4 and 5 illustrate the invention applied to what is known as a garment press, which comprises a hollow heated head 20 which co-operates with a hollow heated bed 21, pressure upon an article between said members being produced by relative movement thereof. The upper member may have a plain metal lower surface or, if desired, 90 may be covered with a layer of canvas 22, while the lower member is provided with a padded surface 23 upon which the article to be pressed is laid. Attached to one edge of the lower pressing member is a cover member 24, which may be suitably secured to said edge such as by buttons, hooks or the like, as may be most convenient. This cover member may be similar to the one before described and consist of an upper canvas layer 25 to which a wool layer 26 is secured, 95 and may be provided with suitable means for detachably connecting it to the other edge of the bed, such as the button fasteners 27.

This press is used by placing the garment upon the bed and covering it with the cover member 24 and then subjecting the article to pressure between the head and bed. The garment is moistened as before either with water or steam applied in any desired manner, the effect being to press the article without the production of an imprint of the canvas or discoloration or running of the color 110 in the article.

What we claim is:—

1. In a pressing machine, a frame, relatively movable upper and lower pressing members between which the work is pressed, the upper member being heated and unpadded, and a woolen layer supported for arrangement between the upper pressing member and the work on the lower pressing member to contact with the upper surface of the 125
- 130

work and avoid imprint thereon or discoloration thereof due to heat and pressure.

2. In a pressing machine, a frame, relatively movable upper and lower pressing members between which the work is pressed, the upper member being heated and unpadded, and a woolen layer separate from the upper pressing member and supported for arrangement between the upper pressing member and the work on the lower pressing member to contact with the upper surface of the work and avoid imprint thereon or discoloration thereof due to heat and pressure.
- 15 3. In a machine for pressing knitted woolen articles, work supporting means including a fabric layer upon which the article is laid, and a cover layer for the article secured along one edge to said fabric layer and provided with means for detachably connecting it thereto along its opposite edge.
- 20 4. In a machine for pressing knitted

woolen articles, work supporting means including a fabric layer upon which the article is laid, and a cover layer for the article secured along one edge to said fabric layer and provided with means for detachably connecting it thereto along its opposite edge, said cover member having a layer of woolen material to directly engage the article.

25 5. In a pressing machine, a work support having a fabric layer to receive the article, and a cover member secured along one edge to said support and provided with a woolen layer to contact with the article.

30 6. In a pressing machine, a work support provided with a rigid frame, a work supporting fabric layer secured thereto, and a cover member for the article secured along one edge to said layer.

35 In testimony whereof we affix our signatures.

DANA H. BENJAMIN.
JAMES P. McCARTHY.
